CLAIM

The ornamental design for a headlamp assembly with adjustable head strap, as shown and described.

DESCRIPTION

FIG. 1 is a top perspective view of a headlamp assembly with adjustable head strap according to the present disclosure.

FIG. 2 is a bottom perspective view thereof.

FIG. 3 is a front side elevation view thereof.

FIG. 4 is a back side elevation view thereof.

FIG. 5 is a left side elevation view thereof.

FIG. 6 is a right side elevation view thereof.

FIG. 7 is a top plan view thereof.

FIG. 8 is a bottom plan view thereof; and,

FIG. 9 is a top perspective view of an alternative embodiment of a headlamp assembly with adjustable head strap according to the present disclosure, in which a battery pack is illustrated in even broken line and all elements illustrated in solid line are identical to those illustrated in solid lines in FIGS. 1-8.

The even broken lines and uneven broken lines form no part of the claimed design. The even broken lines illustrate unclaimed portions of the article and the uneven broken lines represent unclaimed boundary of the claimed design.
